[57] ABSTRACT

A device for handling filled sacks in a stacking machine

comprises a gantry; means for securing the gantry to a transportation device; a platform for supporting the filled sacks, suspended from the gantry so as to be moveable therealong between a forward position and a retracted position; and a fence mounted in a fixed position with respect to the gantry and located above the platform to act as a barrier against movement of any sacks supported on the platform as the latter is withdrawn from the forward to the retracted position.
